SEAM

Norman E. Weeks, Indianapolis, Ind., and Robert B. Le Roy, Rutherford, N. J., assignors to Bemis Bro. Bag Company, St. Louis, Mo., a corporation of Missouri

Application January 22, 1944, Serial No. 519,339

13 Claims.

(Cl. 112—262)

This invention relates broadly to seams for seamed articles in general, and with regard to certain more specific features to closure seams for mouths, bottoms, and the like, of bags, case liners, and the like.

Among the several objects of the invention may be noted the provision of a closure seam employing a sewn cover strip, which, while providing the strength and excellent closing characteristics of such a strip, also allows entry through the strip into the seam of a subsequently applied sealing compound; the provision of a closure seam of the class described which will allow said sealing compound to effect substantially complete inter-ply penetration throughout the edge regions of the closure; the provision of cover material for such a closure seam which may be applied in an ordinary sewing machine without entailing mechanical difficulties; and the provision of a sealed seam in general in which the sealing material is reinforced throughout. Other objects will be in part obvious and in part pointed out hereinafter.

The invention accordingly comprises the elements and combinations of elements, features of construction, and arrangements of parts which will be exemplified in the structures hereinafter described; and the scope of the application of which will be indicated in the following claims.

In the accompanying drawing, in which are illustrated several of various possible embodiments of the invention,

Fig. 1 is a side elevation showing a bag having double-strip mouth and bottom enclosures constituting one form of the invention;

Fig. 2 is an enlarged broken-away detailed plan of the upper right-hand corner of Fig. 1;

Fig. 3 is a further enlarged vertical section taken on lines 3—3 of Figs. 1 and 2;

Fig. 4 is a view similar to Fig. 3 showing an alternative single-strip embodiment, being taken on line 4—4 of Fig. 5;

Fig. 5 is an upper right-hand corner detail similar to Fig. 2 but showing the embodiment of Fig. 4 with a corner of the single cover strip lifted; and,

Fig. 6 is a corner detail similar to Fig. 5 illustrating another embodiment.

Similar reference characters indicate corresponding parts throughout the several views of the drawing.

Referring now more particularly to Fig. 1, there is shown at numeral 1 a five-ply bag. The multiple plies are indicated specifically at numerals 3, 5, 7, 9 and 11 in Figs. 2 and 3. Each of these plies constitutes a tube, usually made of paper, having a longitudinal lap seam 13. Each seam 13 of a given ply is staggered with respect to its neighbor to prevent undue thickening at the longitudinal seams. The tube thus formed is cut into

bag-forming segments, the ends of which are to be closed. The bottom end is closed before filling, and the top end after filling. The problem is to obtain a permanent closure at these or similar points, which is as absolutely water-tight as possible. The prior form of seam 13 shown is satisfactory and the invention does not refer to these. It is to be understood, however, that the new seam is applicable to longitudinal locations such as occupied by seams 13 should such location become desirable. That is, the invention is not limited to locations on the ends of bags.

It has been proposed heretofore to sew an ordinary U-shaped paper cover strip over the mouth 15 of the bag and then to dip the covered mouth into wax. This procedure alone was only partially effective, since the wax was prevented by the cover strip from complete inter-ply penetration and at best simply penetrated somewhat around the needle holes through which the sewing thread passed. We provide hereby a cover strip which performs normal covering and strengthening functions but which also allows subsequent thorough penetration by the sealing material into all parts of the seam to effect complete inter-ply penetration.

Referring to Figs. 1-3, one form of our invention comprises a U-shaped cover strip 15 composed of an inner layer of flannel 17 and an outer layer of preferably starched crinoline 19. The flannel 17 is exemplary of any fluffy, absorbent material adapted to act as a wick. Flannelette is a cotton substitute for the wool flannel, and is also adaptable for the purpose. The crinoline 19 is exemplary of any relatively stiff reticulated covering material having greater strength than the absorbent material. Crinoline is a fabric made of quite open or low-count weave.

The U-shaped composite cover strip assembly composed of the inner wick layer 17 and the outer open-cover layer 19 is applied and closed over the open end of the bag, after which stitching 21 is applied through both sides of the cover strip and the contained bag plies or layers. In order to improve the strength of the stitching 21 a cushioning roving cord 23 may be applied under the stitching on one side of the closure as shown, or on both sides. This cord is applied as the seam is formed by the sewing machine. It is to be understood that for purposes of the invention per se, the roving cord 23 is not absolutely necessary but it is preferable. The roving cord should preferably be of a fluffy and absorbing character. Thus, in addition to its cushioning functions, it also has the desired absorbent wick functions of layer 17.

After the composite cover 15 has been stitched into place, the entire seam is dipped into a proofing material such as melted wax. The wax is preferably amorphous, so that after solidifying it

retains a desired flexibility. If a large degree of flexibility is not important, then a crystalline wax may be used. A suitable wax is one which is marketed under the trade name of "Q 2111," dipping being for a period of the order of six seconds or so at 250° to 260° F. The wax is quite thin when so melted and easily advances by absorption and capillary wick action through the flannel 17 to all parts of the closure. This occurs after free passage through the open weave of the crinoline 10 19. As indicated in Figs. 2 and 3, the wax (indexed 25) progresses right through the composite cover strip throughout its area and creeps into position on opposite sides of the bag, and between the laminations or layers constituting said sides, and in the bag mouth between said sides. The result is the existence of a complete and thorough waterproofing wax impregnation on and within the cover strip, and between all layers adjacent to the bag opening. The stitching 21 also becomes surrounded, impregnated both by action of the wax from the outside and from the interleaved position within the layers. The roving cord 23, being also fluffy and absorbent, encourages absorption of wax.

The relatively stiff crinoline element 19 not only has the function of adding strength to the finished closure but it also presents to the presser foot and needle of the sewing machine a surface upon which these may operate better than they do upon a soft, flexible surface such as flannel, particularly when such surfaces are in strip form, as herein. While the starching is desirable, it is not absolutely necessary to the invention.

Some materials are available which, in a single composite strip, provide the desired absorbent, loose, fluffy inside surface and the stronger, stiffer open weave outside surface. For example, some forms of wool flannel and cotton flannelette are such materials, illustrated in Figs. 4 and 5, indexed 27. They are not starched. They are characterized by an inside fluffy component nap surface shown at 29 and an outside component surface 31 which is not fluffy and is more like an ordinary woven surface in which are reticulations 33 between threads. The application of the strip of Figs. 4 and 5 and its function is analogous to that of the two-piece composite strip of Figs. 1-3.

Another useful material for the purpose is terry cloth. This is a woven material having a loop-formed nap on one side in which the loops are left uncut. Turkish toweling is similar and also useful for the purpose. It has nap on both sides and strong enough to maintain proper alignment in the sewing machine. Fig. 6 illustrates at 35 this type of uncut nap material in general. It is quite absorbent and at the same time allows satisfactory operation of the sewing machine for applying the stitching 21.

While it is preferred that the cover strip be made entirely of fabric, it may be made in part of fabric and in part of a strong paper or paper-like layer. For example, the inside component may be of fluffy cloth and the outside component of kraft paper with holes in it for entry of wax, the holes forming the reticulations.

Equivalents for the wax are other waterproofers such as asphalt for example.

It is to be understood that the invention is applicable to single ply bags in which case the wax penetrates to opposite sides of the bag and creeps into the mouth areas between sides. It is also applicable to fabric bags and those made of fabric and paper.

It will be noted in the drawings that the ends

of the cover strip have been carried beyond the edges of the bag, as indicated at 37. The degree of extension is such as to effect a thorough end closure.

From the above it will be seen that important features of the invention are the provision of a one-piece or multi-piece composite cover strip having the combined characteristics of an outer reticulated but relatively smooth surface functioning first to allow proper operation of a sewing machine in applying the stitching 21, and second to allow free entry to the inside of the strip through-out its entire area of the subsequently applied waterproofer. In addition, the cover has the characteristic inside of being absorbent, fluffy and to function as a wick which will absorb the wax which enters through the reticulation 33 and allow it to progress into position in inter-ply laminar relationship between the bag plies, as well as coating the outside of the bag opening underneath the cover strip. The needle holes of the stitching are also completely closed because they are reached exteriorly and interiorly by wax from all laminations. In other words, the proofing medium finally functions as a solid matrix in which the fabric acts as a reinforcement.

The invention is also applicable to seams for other articles but its application to bags and case liners solves a particular problem in that field. Bags or case liners which are otherwise waterproof and having the new closure seam may be immersed for substantial periods under water.

The principles of the invention are applicable also to seals for use with seams made with flat covering tape, i. e., unfolded and connecting co-planar pieces whether sewn or not. In this case again, the wick-like action of the tape transfers the wax or sealing material through the tape to the inside of the seams and the sealing material impregnates the tape.

Furthermore, regardless of what type of seam the invention is employed on, the fibrous character of the tape actually reinforces the film of wax or sealing material. This is because the fibres are ramified throughout the mass of sealing material. This allows for application of a larger amount of sealing material (wax) without danger of its cracking and flaking away. In fact this allows of applying a sufficient mass of sealing material, in the case of wax, to present to the outside of the seam almost a solid wax surface which will not flake away.

In view of the above it will be seen that the several objects of the invention are achieved and other advantageous results attained.

As many changes could be made in the above constructions without departing from the scope of the invention, it is intended that all matter contained in the above description, or shown in the accompanying drawing, shall be interpreted as illustrative and not in a limiting sense.

We claim:

1. A seam for adjacent layers of material to be joined, comprising a U-shaped cover strip covering the edges and adjacent sides of said layers, said cover strip being composed of material which is absorbent with respect to a proofing medium, stitching passing through the opposite sides of said U-shaped cover strip and said adjacent layers, and proofing medium penetrated throughout said cover strip to and between said layers.
2. A seam for adjacent layers of material to be joined, comprising a U-shaped composite cover strip enclosing the edges and adjacent sides of said layers, said cover strip being composed inside

of material which is absorbent with respect to a proofing medium and outside of relatively stiffer reticulated material, stitching passing through the opposite sides of said composite cover strip and said adjacent layers, and proofing medium interpenetrated throughout both components of said cover strip and between said layers.

3. A seam comprising adjacent layers to be joined, a U-shaped woven fabric cover strip enclosing the edges of said layers, said cover strip being composed of a relatively fluffy inside component which is absorbent to waterproofing material and a relatively stiffer outside component weave presenting reticulation through its weave for passage there-through of said waterproofing material, stitching passing through the sides of the cover strip and the enclosed layers, and waterproofing material impregnating the entire cover strip and lying on and between said enclosed layers throughout the areas enclosed by the cover strip and penetrating the holes caused by the stitching, said components comprising separate elements.

4. A seam comprising adjacent layers to be joined, a U-shaped woven fabric cover strip enclosing the edges of said layers, said cover strip being composed of a relatively fluffy inside component which is absorbent to waterproofing material and a relatively stiffer outside component weave presenting reticulation through its weave for passage there-through of said waterproofing material, stitching passing through the sides of the cover strip and the enclosed layers, and waterproofing material impregnating the entire cover strip and lying on and between said enclosed layers throughout the areas enclosed by the cover strip and penetrating the holes caused by the stitching, said components comprising a single layer of material.

5. A seam comprising adjacent layers of multi-ply material to be joined, a composite cover strip enclosing said multi-ply layers, said cover strip being composed of an absorbent inside component and a reticulated outside component, stitching passing through opposite sides of the cover strip and the enclosed layers, and a waterproofing material extending through said reticulations of the outside component and impregnating said inside component, and extending into the spaces around the contained layers within the cover strip and into the holes caused by the stitching, said waterproofing material forming a matrix when hardened in which the cover strip forms a reinforcement.

6. A closure seam comprising adjacent multi-ply paper sides, a U-shaped fabric cover strip enclosing the edge portions of said sides, said cover strip being composite and comprising a separate inside fluffy absorbent layer and a separate outside relatively smooth layer of low-count weave providing reticulations, stitching passing through the opposite sides of the cover strip and the contained multi-ply paper layers, and waterproofing material impregnating both components of the cover strip and the spaces between the contained multi-ply layers.

7. A closure seam comprising adjacent multi-ply layers of paper, a U-shaped composite fabric cover strip enclosing the edge portions of said layers, said composite cover strip comprising an inside flannel component and an outside starched

crinoline component, stitching passing through opposite sides of said cover strip and the contained multi-ply paper layers and wax impregnating the entire seam.

5 8. A closure seam comprising adjacent layers of multi-ply paper, a U-shaped cover strip enclosing the edges of said paper layers, said cover strip comprising a terry cloth having a nap surface inwardly directed, stitching passing through said cover strip and the contained paper layers and waterproofing material impregnating the closure.

10 9. A closure seam comprising adjacent layers of multi-ply paper, a U-shaped cover strip enclosing the edges of said paper layers, said cover strip comprising turkish-towel material, stitching passing through said cover strip and the contained paper layers and waterproofing material impregnating the closure.

15 10. A closure seam comprising adjacent layers of multi-ply paper, a U-shaped cover strip enclosing the edges of said paper layers, said cover strip comprising a single ply of fabric having a relatively smooth but reticulated outside surface and an inwardly directed rougher absorbent surface, stitching passing through said cover strip and the enclosed paper layers, and waterproofing wax impregnating the cover strip and located within the ply-formed spaces within it.

20 11. A seam for adjacently located areas of material, comprising fabric strip portions attached to opposite sides and joining said areas of material, said strip portions being composed of material which throughout is reticulated and absorbent with respect to a liquid proofing medium, and a liquid proofing medium adapted to solidify and form a matrix and while liquid penetrating throughout said fabric strip portions and extending between said areas said fabric strip portions acting both as wicks for placement of the medium when liquid and as reinforcements therefor when it is solidified as a matrix.

25 12. A seam for adjacent areas of material, comprising a strip attached to and joining said areas, said strip having a fluffy, fibrous and absorbent component directly adjacent to said areas and having a less fluffy reticulated layer on its side directed away from said areas, and a proofing medium impregnating said strip, said outside reticulated layer transmitting the proofing medium to the fluffy layer, and the latter functioning as a wick, the amount of proofing medium supplied being such as to present a substantially solid mass in which the fibres of the fluffy material act as reinforcements.

30 13. A seam for adjacent areas of material, comprising a strip attached to and joining said areas, said strip having a fluffy, fibrous and absorbent component directly adjacent to said areas and having a less fibrous reticulated layer on its side directed away from said areas, and wax impregnating said strip, said outside reticulated layer transmitting the wax to the fluffy, fibrous inner layer, and the latter functioning as a wick for the wax when melted, the amount of wax supplied being such as to present when solidified a substantially solid mass in which the fibres of the fluffy material act as reinforcements.
